DESIGN FOR A CLOCK OR SIMILAR ARTICLE

Margery Cummings, Beverly Hills, Calif.

Application November 29, 1941, Serial No. 104,403

Term of patent 3½ years

To all whom it may concern:

Be it known that I, Margery Cummings, a citizen of the United States, residing in the city of Beverly Hills, in the county of Los Angeles, State of California, have invented a new, original, and ornamental Design for a Clock or Similar Article, of which the following is a specification, reference being had to the accompanying drawing, forming a part thereof.

Figure 1 is a side elevation of a clock or similar article, showing my new design.

Figure 2 is a top plan view of the same.

My design for a clock or similar article as illustrated is characterized by its configuration including the particular placement of the dial and the convex crystal.

I claim:

The ornamental design for a clock or similar article, as shown and described.

MARGERY CUMMINGS.
